US0D1054440S

(12) United States Design Patent (10) Patent No.: US D1,054,440 S
(45) Date of Patent: * Dec. 17, 2024

(54) DISPLAY SCREEN WITH GRAPHICAL USER INTERFACE

(71) Applicant: Airbnb, Inc., San Francisco, CA (US)

(72) Inventors: Aurelio Guzman, San Francisco, CA (US); Damjan Stankovic, San Francisco, CA (US); David Muro, San Francisco, CA (US); Jeduan Alberto Cornejo Legorreta, San Francisco, CA (US); Alejandro Erviti, San Francisco, CA (US); Tony Chan, San Francisco, CA (US); Teofila Connor, San Francisco, CA (US)

(73) Assignee: Airbnb, Inc., San Francisco, CA (US)

() Term: 15 Years

(21) Appl. No.: 29/875,221

(22) Filed: May 1, 2023

(51) LOC (14) Cl. 14-04

(52) U.S. Cl.

USPC D14/485

(57) CLAIM

The ornamental design for a display screen with graphical user interface as shown and described.

DESCRIPTION

The FIGURE is a front view of a display screen with graphical user interface showing our new design.

The peripheral dash-dot-dash lines illustrate a display screen or portion thereof and form no part of the claimed design. The dashed broken lines within the peripheral dash-dot dash lines illustrate portions of the graphical user interface which form no part of the claimed design.

1 Claim, 1 Drawing Sheet
